UNITED STATES PATENT OFFICE.

ARTHUR W. DUDLEY, OF MARLBORO, MASSACHUSETTS.

EDGE-GUIDE ATTACHMENT FOR SEWING-MACHINES.

1,223,860.

Specification of Letters Patent. Patented Apr. 24, 1917.

Application filed April 27, 1916. Serial No. 93,947.

To all whom it may concern:

Be it known that I, ARTHUR W. DUDLEY, a citizen of the United States, residing at Marlboro, in the county of Middlesex and State of Massachusetts, have invented certain new and useful Improvements in Edge-Guide Attachments for Sewing-Machines; and I do hereby declare the following to be a full, clear, and exact description of the invention, such as will enable others skilled in the art to which it appertains to make and use the same.

This invention relates to an edge guide attachment for sewing machines which are used in the fitting room of a shoe making establishment, in the operation of top stitching of shoes and the primary object of the invention is to provide an attachment as specified which is constructed so that it will be simple and easy for the operator to keep on the edge on the top of the upper of the shoe and thereby get an even regular line of stitching, insuring good and uniform work.

Another object of this invention is to provide an attachment or guide as specified which can be instantly thrown out of an operative position at the will of the operator, should the shoe being worked upon require a bar or reinforcement of any kind on the strap and which when thrown into an inoperative position will permit of a clearance of practically two and one-half inches so that it will not in any way bother the operator of the machine.

A further object of this invention is to provide a guide as specified which is constructed for allowing the needle to run as close to the edge of the top of the shoe as the operator may desire.

With the foregoing and other objects in view this invention consists in such novel features of construction, combination and arrangement of parts as will be hereinafter more fully described, illustrated in the accompanying drawing and claimed.

In describing the invention in detail reference will be had to the accompanying drawing wherein like characters designate like

and corresponding parts throughout the 50 several views, and in which:—

Figure 1 is a perspective view of the improved guide.

Fig. 2 is an end view of the guide.

Fig. 3 is a top plan view of the guide 55 showing the same swung into an inoperative position, and

Fig. 4 is a cross section through the guide.

Referring more particularly to the drawing, 1 designates the base or attaching plate 60 of the guide which is provided with a slot 2 and a groove 3 which extends inwardly from one end of the plate and is adapted for receiving a boss 4 which projects downwardly from the under surface of the pivoted supporting block 5. The supporting block 5 is pivotally supported by a pin 6 which is attached to and projects upwardly from the upper surface of the attaching plate 1. The block 5 is mounted upon the pin 6 for vertical movement with respect thereto, and a spiral spring 7 is coiled about the pin and engages the upper surface of an arm 8 which is mounted upon the upper surface of the block 5 and the under surface of a washer 9 75 which washer is mounted upon the pin 6 and is held in place by means of a cotter pin or the like 10. The spring 7 tends to force the under surface of the block 5 in engagement with the upper surface of the attaching plate 1 at all times, and it also forces the block downwardly so that the boss 4 will be seated in the groove 3, when the attachment is in an operative position for preventing accidental rotary movement of the block and 80 the structure carried thereby.

A cam 11 is pivotally connected to the block 5 as shown at 12 and it has a thumb piece 13 formed thereon, by means of which the cam is rocked. The cam 11 is provided with a rounded shoulder 14 which engages the upper surface of the attaching plate 1 so that when the thumb handle or rest 13 is moved downwardly, the rounded shoulder 14 will ride upon the upper surface of the 90 plate 1 and force the block 5 upwardly out of engagement with the upper surface of the plate 1 so as to permit the block to be swung

into a transversely extending position as illustrated in Fig. 3 of the drawing. A pin 15 is carried by the attaching plate 1 and it limits the pivotal movement of the block 5.

- 5 The arm 8 is provided with an opening 17 formed therein, which opening receives the rolled end 18 of a guide arm 19. A pin 20 extends through the rolled end 18 and through the plate 8 for pivotally connecting 10 the guide arm 19 to the guide arm 8. The arm 19 is provided with a slot 21 formed therein which receives a guide pin 22 carried by the arm 8 adjacent to its outer end. A set or thumb screw 23 is threadably carried 15 by the guide arm 19 and its under or inner end engages the upper surface of the guide arm 8 for holding the arm 19 in various adjusted pivotal positions with respect to the arm 8. A spiral spring 24 is coiled about 20 the thumb screw 23 and engages the upper surface of the guide arm.

A spring or resilient wire 25 has one end attached to the upper surface of the arm 8 by means of a screw 26 and its other end extending transversely across and engaging the upper surface of the arm 19 as shown at 27.

The outer end of the guide arm 19 is bent downwardly as shown at 28, and further as 30 shown at 29 to provide a portion 30 which extends substantially at right angles to the surface of the plate 1 and also the arm 8. The outer surface of the transversely extending portion 30 is provided with a groove 35 31, which forms a guide for the needle of the sewing machine when the guide is adjusted so that the article being sewed will be stitched very close to its edge.

The edge guide is adjustably attached to 40 the table A of a sewing machine by means of thumb screws B which extend through the slot 2 and the angled end 30 of the guiding arm 19 is positioned so that the edge of the article being sewed will engage the outer 45 surface of the angled end 30, thereby maintaining a uniform distance between the edge of the article being sewed and the needle C of the sewing machine. The distance between the end 30 and the needle C may be 50 varied as desired by loosening the thumb screws B and sliding the attaching plate 1 either toward or away from the needle C as desired.

When it is necessary to sew inwardly from 55 the edge of the article being worked upon, the cam 11 is rocked through the medium of the thumb piece 13 and the block 5 is rotated or swung about on the pin 6 for positioning the guiding arm 19 and the plate 8 60 at right angles to their normal operative positions.

From the foregoing description taken in connection with the accompanying drawing, the advantages of construction and of the

method of operation of the improved edge 65 guide attachment for sewing machines will be readily apparent to those skilled in the art to which this invention appertains, and while in the foregoing description, the principle of the operation of this invention has 70 been described together with various features of construction, it is to be understood that certain minor features of construction, combination and arrangement of parts may be altered to suit practical conditions 75 provided such alterations are comprehended within the scope of what is claimed.

What is claimed is:—

1. In an edge guide for sewing machines, a plate adjustably connected to the table of 80 a sewing machine, a block rotatably carried by said plate, a plate attached to the upper surface of said block, a guide arm pivotally connected to said plate and extending outwardly therefrom, said guide arm having 85 its outer free end bent to form a vertical edge guide and provided with a vertically extending needle guiding recess in its outer face.

2. In an edge guide for sewing machines, 90 an attaching plate adjustably connected to the table of a sewing machine, a block rotatably carried by said attaching plate, a plate attached to the upper surface of said block, a guide arm pivotally connected to said plate and extending outwardly therefrom, 95 said guide arm having its outer free end bent to form a vertical edge guide and provided with a vertically extending needle guiding recess in its outer face, a thumb screw connected to said guide arm for pivotally moving it with respect to said plate, said thumb screw holding said guide arm in 100 adjusted pivotal position.

3. In an edge guide for sewing machines, 105 an attaching plate adjustably connected to the table of a sewing machine, a block rotatably carried by said attaching plate, a plate attached to the upper surface of said block, a guide arm pivotally connected to 110 said plate and extending outwardly therefrom, said guide arm having its outer free end bent to form a vertical edge guide and provided with a vertically extending needle guiding recess in its outer face, a thumb screw connected to said guide arm for pivotally moving it with respect to said plate, 115 said thumb screw holding said guide arm in adjusted pivotal positions, and a spring connected to said plate and to said guide arm for holding said guide arm against accidental upward pivotal movement.

4. In an edge guide for sewing machines, 120 an attaching plate provided with a groove extending inwardly in the upper surface of the same, a pin carried by said attaching plate, a block pivotally mounted upon said pin for permitting of a limited vertical 125

- movement of the block with respect to the plate, a boss projecting downwardly from the under surface of said block and adapted for seating in said recess for preventing accidental pivotal movement of said block with respect to said plate, a cam pivotally carried by said block and engaging the upper surface of said plate, a thumb rest connected to said cam for pivotally moving the cam for moving the under surface of said block out of facial engagement with the upper surface of said plate to permit of pivotal movement of the block, and means for automatically moving said block downwardly into engagement with said plate upon release of pressure from said cam.
5. In an edge guide for sewing machines, an attaching plate provided with a groove extending inwardly in the upper surface of the same, a pin carried by said attaching plate, a block pivotally mounted upon said pin for permitting of a limited vertical movement of the block with respect to the plate, a boss projecting downwardly from the under surface of said block and adapted for seating in said recess for preventing accidental pivotal movement of said block with respect to said plate, a cam pivotally carried by said block and engaging the upper surface of said plate, a thumb rest connected to said cam for pivotally moving the cam for moving the under surface of said block out of facial engagement with the upper surface of said plate to permit of pivotal movement of the block, and means for automatically moving said block downwardly into engagement with said attaching plate upon release of pressure from said cam, a second upstanding pin carried by said plate and adapted for limiting the pivotal movement of said block, said plate being provided with a slot formed therein, a plate attached to the upper surface of said block, and a guiding arm pivotally connected to said plate and projecting outwardly therefrom, said guiding arm having its outer end bent downwardly and provided with a needle guiding recess formed in its outer surface.
6. In an edge guide for sewing machines, an attaching plate provided with a groove extending inwardly in the upper surface of the same, a pin carried by said attaching plate, a block pivotally mounted upon said pin for permitting of a limited vertical movement of the block with respect to the attaching plate, a boss projecting downwardly from the under surface of said block and adapted for seating in said recess for preventing accidental pivotal movement of said block with respect to said plate, a cam pivotally carried by said block and engaging the upper surface of said plate, a thumb rest connected to said cam for pivotally moving the cam for moving the under surface of said block out of facial engagement with the upper surface of said plate to permit of pivotal movement of the block, and means for automatically moving said block downwardly into engagement with said attaching plate upon release of pressure from said cam, a second upstanding pin carried by said plate and adapted for limiting the pivotal movement of said block, said plate being provided with a slot formed therein, a plate attached to the upper surface of said block, a guide arm pivotally connected to said plate and projecting outwardly therefrom, said guide arm having its outer end bent downwardly and provided with a recess formed in its outer surface, a thumb screw adjustably carried by said guiding arm and adapted for engagement with said plate for holding said guiding arm in adjusted position.
7. In an edge guide attachment for sewing machines, an attaching plate provided with a groove extending inwardly in the upper surface of the same, a pin carried by said attaching plate, a block pivotally mounted upon said pin for permitting of a limited vertical movement of the block with respect to the attaching plate, a boss projecting downwardly from the under surface of said block and adapted for seating in said recess for preventing accidental pivotal movement of said block with respect to said plate, a cam pivotally carried by said block and engaging the upper surface of said plate, a thumb rest connected to said cam for pivotally moving the cam for moving the under surface of said block out of facial engagement with the upper surface of said plate to permit of pivotal movement of the block, and means for automatically moving said block downwardly into engagement with said attaching plate upon release of pressure from said cam, a second upstanding pin carried by said plate and adapted for limiting the pivotal movement of said block, said plate being provided with a slot formed therein, a plate attached to the upper surface of said block, a guide arm pivotally connected to said plate and projecting outwardly therefrom, said guide arm having its outer end bent downwardly and provided with a recess formed in its outer surface, a thumb screw adjustably carried by said guiding arm and adapted for engagement with said plate for holding said guiding arm in adjusted position.
8. In an edge guide attachment for sewing machines, an attaching plate provided with a groove extending inwardly in the upper surface of the same, a pin carried by said attaching plate, a block pivotally mounted upon said pin for permitting of a limited vertical movement of the block with respect to the attaching plate, a boss projecting downwardly from the under surface of said block and adapted for seating in said recess for preventing accidental pivotal movement of said block with respect to said plate, a cam pivotally carried by said block and engaging the upper surface of said plate, a thumb rest connected to said cam for pivotally moving the cam for moving the under surface of said block out of facial engagement with the upper surface of said plate to permit of pivotal movement of the block, and means for automatically moving said block downwardly into engagement with said attaching plate upon release of pressure from said cam, a second upstanding pin carried by said plate and adapted for limiting the pivotal movement of said block, said plate being provided with a slot formed therein, a plate attached to the upper surface of said block, a guide arm pivotally connected to said plate and projecting outwardly therefrom, said guide arm having its outer end bent downwardly and provided with a recess formed in its outer surface, a thumb screw adjustably carried by said guiding arm and adapted for engagement with said plate for holding said guiding arm in adjusted position.

4

out of facial engagement with the upper surface of said attaching plate to permit of pivotal movement of the block, means for automatically moving said block downwardly into engagement with said attaching plate upon release of pressure from said cam, a second upstanding pin carried by said plate and adapted for limiting the pivotal movement of said block, said plate being provided with a slot formed therein, a plate attached to the upper surface of said block, a guiding arm pivotally connected to said plate and projecting outwardly therefrom, said guiding arm having its outer end 15 bent downwardly and provided with a recess formed in its outer surface, a thumb screw adjustably carried by said guiding arm and adapted for engagement with said plate for holding said guiding arm in adjusted position, a spring rod carried by said plate and engaging said guiding arm for automatically moving said guiding arm downwardly into engagement with plate.

9. In an edge guide for sewing machines, 25 an attaching plate adjustably connected to the table of a sewing machine, a block rotatably carried by said attaching plate, a plate attached to the upper surface of said block, a guide arm pivotally connected to said plate and extending outwardly therefrom, said guide arm having its outer free end bent to form a vertical edge guide and provided with a vertically extending needle guiding recess in its outer face, a spring 35 connected to said plate and to said guide arm for holding said guide arm against accidental pivotal movement.

10. In an edge guide sewing machine, an attaching plate adjustably connected to the 40 table of a sewing machine, a block rotatably carried by said plate, means for preventing rotation of said block, a plate carried by said block, a guiding arm pivotally connected to said plate and projecting outwardly therefrom, a spring connected to said plate 45 and engaging said guiding arm outwardly of its pivot for preventing accidental upward pivotal movement of said arm.

11. In an edge guide for sewing machines, 50 an attaching plate adjustably connected to the table of a sewing machine, a block rotatably carried by said plate, means for preventing rotation of said block, a plate carried by said block, a guiding arm pivot- 55 ally connected to said plate and extending outwardly therefrom, a spring connected to said plate and engaging said guiding arm outwardly of its pivot for preventing accidental upward pivotal movement of said arm, a thumb screw carried by said guiding arm and engaging the upper surface of said plate for pivotally moving said arm with respect to said plate and holding said arm 60 in adjusted pivotal position.

12. In an edge guide for sewing machines, 65 an attaching plate adjustably connected to the table of a sewing machine, a block rotatably carried by said plate, means for preventing rotation of said block, a plate carried by said block, a guiding arm pivotally 70 connected to said plate and extending outwardly therefrom, a spring connected to said plate and engaging said guiding arm outwardly of its pivot for preventing accidental upward pivotal movement of said 75 arm, a thumb screw carried by said guiding arm and engaging the upper surface of said plate for pivotally moving said arm with respect to said plate and holding said arm in adjusted pivotal positions, means for releasing the means for preventing rotation of said block to permit said block to be rotated upon said attaching plate for swinging said guiding arm into an inoperative position, and means for limiting the rotary movement 80 of said block.

13. In an edge guide for sewing machines, an attaching plate provided with a groove 85 extending inwardly in the upper surface of the same, a pin carried by said attaching plate, a block pivotally mounted upon said pin for permitting of vertical limited movement of the block with respect to said attaching plate, a boss projecting downwardly 90 from the under surface of said block and adapted for seating in said recess for preventing accidental pivotal movement of said block with respect to said attaching plate, a cam pivotally carried by said block and 95 engaging the upper surface of said attaching plate, a thumb rest connected to said cam for pivotally moving the cam for moving the under surface of the block out of facial engagement with the upper surface of said attaching plate to permit of pivotal movement 100 of the block.

14. In an edge guide for sewing machines, an attaching plate provided with a groove extending inwardly in the upper surface of the 110 same, a pin carried by said attaching plate, a block pivotally mounted upon said pin for permitting of vertical limited movement of the block with respect to said attaching plate, a boss projecting downwardly from 115 the under surface of said block and adapted for seating in said recess for preventing accidental pivotal movement of said block with respect to said attaching plate, a cam pivotally carried by said block and engaging the upper surface of said attaching plate, a thumb rest connected to said cam for pivotally moving the cam for moving the under surface of the block out of facial engagement with the upper surface of said attaching plate to permit of pivotal movement 120 of the block, a plate attached to the upper surface of said block, a guide arm pivotally connected to said plate and ex- 125

tending outwardly therefrom, said guide arm having its outer free end bent to form a vertical edge guide and provided with a vertically extending needle guiding recess 5 in its outer end, means for pivotally moving said guide arm with respect to said plate, said means holding said guide arm in adjusted pivotal position and means connected to said plate and engaging said guide arm for holding said guide arm against accidental upward pivotal movement.

In testimony whereof I affix my signature in presence of two witnesses.

ARTHUR W. DUDLEY.
